UNITED STATES PATENT OFFICE.

THOMAS JOSEPH STURTEVANT, OF WELLESLEY, MASSACHUSETTS, ASSIGNOR TO
STURTEVANT MILL COMPANY, A CORPORATION OF MAINE.

VERTICAL CRUSHING-MILL.

1,198,597.

Specification of Letters Patent. Patented Sept. 19, 1916.

Application filed June 24, 1916. Serial No. 105,739.

To all whom it may concern:

Be it known that I, THOMAS J. STURTEVANT, a citizen of the United States, residing at Wellesley, in the county of Norfolk 5 and State of Massachusetts, have invented or discovered certain new and useful Improvements in Vertical Crushing-Mills, of which the following is a specification, reference being had therein to the accompanying drawings.

This invention relates to vertical crushing mills of that class shown in the Sturtevant Patents Nos. 761,334; 857,121 and 1,105,712, and the invention has for its object to improve this class of mills in such a manner as to render them more convenient in mounting or dismounting the parts, as well as to improve their efficiency; all as will hereinafter more fully appear.

20 In the accompanying drawings Figure 1 is a vertical section of the improved vertical crushing mill. Fig. 2 is a plan view of the same, and Fig. 3 is a plan view of the base portion of the casing thereof.

25 Referring to the drawings, 12 denotes the base or lower part of the casing which is provided with a horizontal flange 13 which, in practice, will be bolted to suitable supports, as timbers 14, which may be more or less elevated for convenience of access to the mill from the bottom thereof. Secured to the flange 13 is a spider 15 which is provided with ears 16 arranged below the said flange and through which ears and said 30 flange pass attaching bolts 17. Interposed between these ears and flange are spacing washers 17^a, the purpose of which will be hereinafter indicated.

The vertical mill shaft 18 is stepped in a 40 sleeve bearing 19 fitting in a central opening in the spider 15 and resting on an adjusting lever 20, similar to the adjusting levers in the forms of mill shown in the Sturtevant patents above referred to. On the shaft 18 and supported by the spider 15 is a bevel gear 21 with which meshes a smaller bevel gear 22 carried by the driving shaft 23. The upper end of the hub of the bevel gear 21 is received in a central recess in a sleeve 24 45 mounted on the shaft 18 to rotate therewith, the overlapping parts of the said hub and sleeve forming a dust-lock for preventing grit or dust from coming in contact with said shaft 18 at this point. The hub of the 50 spider 15 is provided with an upwardly pro-

jecting flange 15^a which is received in a recess 21^a in the bottom of the hub of the bevel gear 21. This construction affords an oil well which is protected from dust by the overlapping parts of the said flange and 55 bevel gear.

The upper part of the shaft 18 is formed rectangular, and preferably square, so that all of the parts, as the crushing cones and nuts 25, 26, 27 and 28 will rotate with said shaft without being otherwise keyed thereto, but, being loosely strung on said shaft, may be readily placed thereon or removed therefrom, and this is also true with reference to the hub of the scraper or sweeper 29, which 60 discharges the crushed material from the lower part of the chamber of the mill through the three outlet spouts 30^a with which the lower part of the casing of the mill is preferably provided. The hub of the scraper or sweeper 29 rests on the top of the sleeve 24, and the lower part of the mill casing is provided with an upwardly projecting flange 12^a projecting into an annular recess 29^a in the hub of the said 65 scraper or sweeper, this construction affording a dust-lock at this point.

The upper part of the mill casing consists of two hinged halves or door-like parts 30 which are pivotally mounted on posts 31 as in the form of mill shown in the Sturtevant Patent No. 1,105,712, so that when these two hinged halves of the upper part of the mill casing are unbolted and the strap or yoke 32, engaging lugs on said halves is removed, 70 these hinged parts of the casing may be swung aside horizontally like doors for convenient access to the upper part of the mill chamber. The stationary crushing lining elements or cones 33 are attached to the insides of the hinged casing parts 30. The shaft 18 has its upper bearing in a sleeve or bearing block 34 which is received between the top portions of the casing parts 30, said sleeve or bearing block being preferably provided near its top with a pocket 35 for the reception of oil, said pocket being closed by a screw-plug 36.

In this improved form of mill, in which the spider 15 is secured beneath the flange 13 of the base portion of the mill casing, the bearing sleeve 19, the gears 21 and 22 and the sleeve 24 may be dismounted from the shaft and taken out from beneath, when the bolts 17, the spider 15 and the lever 20, 105 110

supporting the said bearing sleeve, have been removed. Of course, in assembling the mill, all of these parts may be introduced from beneath. This is a great convenience, as will be understood, as it avoids the inconvenience incidental to inserting or removing these parts from above, as heretofore. Also, by virtue of this construction, the vertical position of the spider 15 and consequently the mesh of the gears 21 and 22 may be varied by using spacing washers 17^a of different thicknesses on the bolts 17, or a greater or lesser number of said washers, these washers, as hereinbefore stated, being interposed between the ears 16 on the spider 15 and the flange 13 on the base portion of the mill casing. Also the mesh of the gears 21 and 22 may be varied, to compensate for wear or for securing a proper relative adjustment of these gears by interposing different thicknesses of bearing washers 37 in the oil well between the hub of the spider 15 and the hub of the bevel gear 21.

From the foregoing it will be understood that the improved construction described affords means whereby all of the parts of the mill may be conveniently assembled or dismounted, all of the parts in the lower portion of the mill casing being insertible and removable from below, while all of the crushing parts on the shaft 18 in the upper portion of the casing may be readily lifted out or removed vertically when the hinged casing door-like parts 30 are swung aside, or may be removed horizontally, if desired, if the shaft be lifted out; and may also be conveniently assembled in a reverse manner.

Having thus described my invention I claim and desire to secure by Letters Patent:

1. In a vertical crushing mill, the combination with a base portion of the mill casing, of a spider secured to the lower side of

said base portion, so that it may be inserted 45 in place or removed from beneath, said spider having a central hub or sleeve adapted to receive the lower bearing for the mill shaft.

2. In a vertical crushing mill, the combination with a base portion provided with a horizontal flange, of a spider having ears disposed beneath said flange, and bolts passing through said ears and flange whereby said spider is removably secured in place 55 beneath said flange.

3. In a vertical crushing mill, the combination with a base portion provided with a horizontal flange, of a spider having ears disposed beneath said flange, and bolts passing through said ears and flange whereby said spider is removably secured in place 60 beneath said flange, and spacing washers between said ears and flange, whereby by using more or less or thicker or thinner 65 washers, the vertical position of said spider may be varied.

4. In a vertical crushing mill, the combination with the base portion of the casing thereof, of a spider removably mounted 70 beneath said base portion and having a central hub or sleeve, a bearing sleeve received in the said hub or sleeve of said spider, a bevel gear above the said spider, a smaller driving bevel gear meshing with the first-named bevel gear, a vertical shaft stepped in said bearing sleeve, and a sleeve on said shaft above said first-named bevel gear, all 75 of said parts excepting said shaft, being insertible into or removable from said mill 80 casing from beneath.

In testimony whereof I affix my signature in presence of two witnesses.

THOMAS JOSEPH STURTEVANT.
